UNITED STATES PATENT OFFICE.

JOHN SEDAJ, OF KENOSHA, WISCONSIN.

EXTENSIBLE TABLE.

1,086,232.

Specification of Letters Patent.

Patented Feb. 3, 1914.

Original application filed April 8, 1912, Serial No. 689,101. Divided and this application filed June 22, 1912. Serial No. 705,157.

To all whom it may concern:

Be it known that I, JOHN SEDAJ, a subject of the King of Hungary, but who have declared my intention of becoming a citizen 5 of the United States, and a resident of the city of Kenosha, county of Kenosha, and State of Wisconsin, have invented certain new and useful Improvements in Extensible Tables, of which the following is a specification.

10 My invention relates to improvements in extensible tables, and more specifically to improvements in means for locking a folding leg of a table in operative position, the 15 present application being a division of my pending application Serial No. 689,101, filed April 8th, 1912, for extensible tables.

The object of my invention is the production of leg locking means of the character 20 mentioned which will be durable and economical in construction and efficient in use.

Other objects will appear hereinafter.

With these objects in view my invention 25 consists in the combinations and arrangements of parts hereinafter described and claimed.

30 My invention will be more readily understood by reference to the accompanying drawing forming a part of this specification, and in which—

Figure 1 is a sectional side elevation of 35 an extensible table embodying my invention, Fig. 2 is a fragmentary perspective view of the extension section of the table detached, showing the same inverted to expose the locking mechanism which constitutes the subject matter of this invention, Fig. 3 is a perspective view of the lower end portion 40 of one of the brace rods included in the invention, and Fig. 4 is a perspective view of the socket member coöperating with said brace rod.

The preferred form of construction, as 45 illustrated in the drawing, comprises a table consisting of a main section 1 and an extension section 2, one edge of the extension section being releasably connected with the main section, as shown in Fig. 1.

50 The extension section 2 consists of a rectangular top 3 at the under side of which is provided a foldable leg 4 which is hingedly secured at 5 to said top adjacent the outer edge thereof. The leg 4 is held in

55 extended or operative position through the

medium of brace rods 6, corresponding ends of which are pivotally secured to the opposite sides of said leg, as clearly shown in Fig. 2. The opposite or free ends of brace rods 6 are formed with laterally projecting 60 portions 7 which are adapted to releasably engage sockets 8 formed in blocks 9 secured upon the base members 10 which are fastened upon the under side of the table top, as shown. Said brace rods, when the ends 65 7 thereof are engaging the sockets 8, will be adapted to securely hold the leg 4 in operative position against relative swinging. The ends 7 of said brace rods are releasably held in engagement with the sockets 8 through 70 the medium of a flexible strip 11 which is mounted at its center upon a block 12 which is fastened medially upon the under side of the table top. The ends of strip 11 are adapted to engage against the inner sides 75 of the lower end portions of brace rods 6 so as to prevent inward movement thereof and hence so as to prevent disengagement of the portions 7 of said rods from the sockets 8. The construction is such, however, that disengagement of said rod ends 80 may be effected by simply flexing the ends of the strip 11 downwardly, as shown in dotted lines in Fig. 2, since, by such flexing the ends of said strip will be lowered out 85 of engagement with said rod ends, so as to permit of the latter being moved inwardly as desired. When the brace rods 6 are disengaged from the blocks 9, the leg 4 will 90 be permitted to be folded against the under side of the table top so as to occupy a minimum space for storage. The table top 3 is reinforced by longitudinally extending cleats 13 which are secured upon the under side thereof adjacent the lateral edges of 95 said top.

A locking mechanism of the construction set forth is durable and economical, and is of high efficiency in operation.

While I have illustrated and described 100 the preferred form of construction for carrying my invention into effect, this is capable of variation and modification without departing from the spirit of the invention. I, therefore, do not wish to be limited 105 to the exact details of construction set forth, but desire to avail myself of such variations and modifications as come within the scope of the appended claims.

Having described my invention, what I 110

claim as new and desire to secure by Letters Patent, is:

1. A table comprising a top; a foldable leg hingedly secured to said top; a brace rod for releasably securing said leg in operative position, one end of said brace rod being pivotally secured to said leg; a laterally opening socket provided at the under side of said table top, the opposite end of said brace rod being bent laterally for engagement with said socket; and a flexible strip adapted normally to lock said brace rod in engagement with said socket, said strip being adapted to be flexed to effect release of said brace rod, substantially as described.
2. A table comprising a top; a foldable leg hingedly secured to said top; a brace rod for releasably securing said leg in operative position, one end of said brace rod being pivotally secured to said leg, the opposite end of said rod being adapted to releasably engage a socket provided at the under side of said table; and a flexible strip arranged upon the under side of said table top and having a free end adapted to normally engage said last mentioned end of said brace rod to hold the same in engagement with said socket, said end of said strip being

adapted to be flexed to permit of release of said last mentioned end of said brace rod from said socket, substantially as described.

3. A table comprising a top; a foldable leg hingedly secured to said top; a pair of brace rods for releasably securing said leg in operative position, corresponding ends of said rods being pivotally secured to said leg, the opposite ends of said rods being adapted to releasably engage sockets provided at the under side of said table top; and a flexible strip fastened upon the under side of said table top with its respective ends free and adapted normally to engage said last mentioned ends of said brace rods to hold the same in engagement with said sockets, said ends of said strip being adapted to be manually flexed to permit of release of said brace rods from said sockets, substantially as described.

In testimony whereof I have signed my name to this specification in the presence of two subscribing witnesses.

JOHN SEDAJ.
